(57) **CLAIM**

We claim the ornamental design for a blade for a reciprocating saw, as shown and described.

DESCRIPTION

FIG. 1 is front view of a blade for a reciprocating saw according to one embodiment with the back view being a mirror image; and,

FIG. 2 is another front and back view of a blade for a reciprocating saw according to another embodiment with the back view being a mirror image.

The dashed broken lines depict portions of the blade for a reciprocating saw that form no part of the claimed design. The dot-dash broken lines represent the boundary of the claimed design and form no part of the claim.
